G. A. AIKEN

SHOE RACK

Filed Nov. 20, 1923

Fig. 1.

Inventor
Glen A. Aiken

By *Karen C. Mueller*

Attorney

UNITED STATES PATENT OFFICE.

GLEN A. AIKEN, OF PITTSBURGH, PENNSYLVANIA.

SHOE RACK.

Application filed November 20, 1923. Serial No. 675,882.

To all whom it may concern:

Be it known that I, GLEN A. AIKEN, a citizen of the United States, residing at Pittsburgh, in the county of Allegheny, 5 State of Pennsylvania, have invented certain new and useful Improvements in Shoe Racks; and I do hereby declare the following to be a full, clear, and exact description of the invention, such as will enable others 10 skilled in the art to which it appertains to make and use the same.

This invention relates to new and useful improvements in racks and more particularly to that type designed for supporting 15 shoes and the like.

The primary object of the present invention is to provide a device of this character which will properly and neatly support shoes and the like in a closet or elsewhere 20 in a home by being attached to a wall or door, the advantages of such a device for supporting articles of this nature, over keeping them on the floor, being obvious.

Another object of the present invention 25 is to provide a device of this character which, while so constructed as to reduce the cost of manufacture to a minimum, will, nevertheless, prove thoroughly strong, durable and practical.

With these and other objects in view, as 30 will become more apparent as the description proceeds, the invention resides in a novel construction and arrangement of parts, a preferred embodiment of which is 35 shown in the accompanying drawing, wherein—

Figure 1, is a view, in elevation, of a shoe 35 rack constructed in accordance with the present invention, and,

Fig. 2, is a view taken on line 2—2 of 40 Figure 1.

Referring particularly to the accompanying drawing, 10 designates a pair of side arms or brackets, each of which is formed 45 from a single length of material, and each of which includes an approximately horizontal portion 11 and the outwardly and downwardly curved portion 12. The free end of each of the approximately horizontal 50 portions 11 is turned angularly at 13

and provided with nail or screw receiving openings 14, whereby the bracket may be attached to a wall, door or the like. In addition to the attaching portion 13, this end is also formed with a struck out tongue 55 15, which is extended in the same plane as the portion 13, but in the opposite direction for the purpose of engaging the wall to prevent downward rocking movement of the bracket. 60

Secured to and connecting the free ends of the curved portions 12, is a bar or rod 16, which, in the operation of the device, is arranged to receive the soles of the shoes or the like thereagainst. Secured to and 65 connecting the inner ends of the curved portions 12, immediately adjacent the junction with the approximately horizontal portions 11, is a heel engaging rod or bar 17. It will be noted that the bar 17 is disposed 70 with its major portion in an approximately vertical plane and that the ends of the bar are twisted out of the plane of the major portion thereof, so that they may lie flatly 75 against the lower faces of the portions 12. The ends of the bar 16 are also secured to and lie flat against the inner faces of the portions 12, while that portion of the bar intermediate the brackets is twisted at an oblique angle. The ends of the bars 16 and 80 17 are secured to the brackets by any desirable means, or method, that of welding being preferred.

It will be understood that the shoe or the like to be supported are placed so that their 85 heels engage the bar 17, while the soles thereof rest against the bar 16.

What is claimed is:

1. As an article of manufacture, a shoe 90 rack comprising a pair of longitudinally bowed side arms, each being formed from a single length of material and having a horizontal portion, the free end of which is formed with an upwardly deflected attaching ear and a downwardly projecting supporting tongue in alignment with said ear, and a pair of supporting bars extending between and connecting the said arms. 95

2. As an article of manufacture, a shoe 100 rack comprising a pair of longitudinally

bowed side arms, each being formed from a single length of material and having a horizontal portion, the free end of which is formed with an upwardly deflected attaching ear positioned at substantially right angles thereto and a downwardly projecting supporting tongue in alignment with said ear, a bar extending between and connecting the plain ends of the arms and a second bar

extending between and connecting the arms ¹⁰ immediately adjacent the said horizontal portions.

In testimony whereof, I affix my signature, in the presence of two witnesses.

GLEN A. AIKEN.
